UNITED STATES PATENT OFFICE.

HERMAN LEVOY AND FRANK DAGWELL, OF CINCINNATI, OHIO.

AUTOMATIC EXTINGUISHER FOR CAR-STOVES.

SPECIFICATION forming part of Letters Patent No. 404,420, dated June 4, 1889.

Application filed January 29, 1889. Serial No. 298,032. (No model.)

To all whom it may concern:

Be it known that we, HERMAN LEVOY and FRANK DAGWELL, both citizens of the United States, residing at Cincinnati, in the 5 county of Hamilton and State of Ohio, have invented certain new and useful Improvements in Automatic Extinguishers for Car-Stoves; and we do declare the following to be a full, clear, and exact description of the invention, reference being had to the accompanying drawings, which form a part of this specification.

The object of our invention is to provide an extinguisher that will automatically discharge 15 a stream of water into a car-stove the instant a collision occurs, and thereby prevent the additional horrors of a conflagration. To accomplish this result we provide an elevated tank or reservoir, which is so suspended from the 20 end, side, or ceiling of the car as not to be affected by the vibrations of the latter, and said reservoir has at its bottom a valve-guarded pipe leading into the stove or similar heater. This valve has a stem, the upper end of which 25 is permanently secured to the ceiling or to any attachment to the upper part of the car, and when the apparatus is in its normal position this stem holds the valve to its seat in the suspended reservoir, thereby preventing wa- 30 ter or other extinguishing-fluid escaping into the stove; but the instant a collision occurs the crushing in of the end or side of the car, or the upheaval of the ceiling or floor of the same, so changes the position of the reservoir 35 or stem as to cause an opening of the valve, and a consequent discharge of water directly into the stove, as hereinafter more fully described.

In the annexed drawings, Figure 1 is a per- 40 spective view of one end of a passenger-car provided with our improved extinguisher, a portion of the stove being sectioned. Fig. 2 is an enlarged sectional elevation of the tank or reservoir and its attachments.

45 A represents the floor, B the end, C the side, and D the ceiling or roof, of a passenger-car, which floor has any approved form of stove or other heater E immovably secured thereto.

F is a tank or reservoir for containing water 50 or any other fire-extinguishing fluid, which tank is freely suspended from springs G G', attached to brackets H H', projecting from the

end and side of the car. This tank is preferably a cylinder having at bottom a seat I for the valve J, which latter is carried by a 55 stem K, occupying an axial position within said tank, the upper end of this stem being secured to the ceiling or roof of the car or to an attachment of the same.

L is a slot in the upper head of the tank, 60 which slot affords room for the passage of the valve-stem, and also serves as a filling-orifice.

M is a rigid discharge-pipe leading from the tank to the upper part of the stove E. The discharging end of this pipe traverses a collar N, which is bolted to the stove, the opening in said collar being of such a size as to permit a limited play or movement of said pipe.

This apparatus is preferably located in a corner of the car, the bracket H being attached 70 to the end B, and the other bracket H' being secured to the side C of the car. The springs G G' are then arranged so as to normally elevate the tank and thus maintain the valve J against the seat I, which valve cannot shift 75 from its proper position, because the stem K is secured to the ceiling D. Furthermore, the tank is coupled to the stove E by the metallic pipe M. After these various parts are thus arranged, the tank F is charged with water or 80 other fire-extinguishing fluid, as seen in Fig. 2, and the apparatus is ready for use.

From the above description it is evident that the springs G G' serve as yielding supports, that compensate for the ordinary vibrations 85 of the car, and thus prevent the valve J being opened when there is no necessity for the fire in the stove being extinguished; but the instant a collision occurs said valve is automatically opened. If the collision should result in 90

smashing the end B of the car, the bracket H would naturally fall, thereby canting the reservoir F over to one side, on account of the pipe M playing sufficiently within the collar N, and allowing such an opening between the 95 valve J and its seat I as to discharge the contents of said reservoir directly into the stove E, with the result of speedily extinguishing the fire in the latter. Any smashing in of the side C of the car would cause the other bracket 100 H' to drop, and then the apparatus would operate, as above described; but if the roof D of the car should be lifted the valve J would then be pulled out of its seat I, and the water

would at once run into the stove and put out the fire. An upheaval of the floor A would produce a similar result, because the stove E is connected to the tank F by the metallic 5 pipe M, and therefore any pitching of said stove, either to the front or rear or to the right or left, would throw said tank out of its normal perpendicular position and cause a discharge of its fluid contents; hence it is apparent that our apparatus is at all times ready 10 for use, and is automatically brought into service the instant it is needed and without requiring the attention of any of the train-men.

We claim as our invention—

15 1. In combination with a car-stove, a tank suspended by yielding supports, a pipe leading from the discharge-opening of said tank to said stove, a valve controlling said opening, and a stem that connects said valve with the 20 upper part of the car, substantially as herein described.

2. In combination with a car-stove, as E, the tank F, suspended by springs G G', attached to brackets H H', a pipe M, leading from the seat I of said tank to said stove, a 25 valve J, controlling the opening of said seat, and a stem K, that connects said valve with the upper part of the car, as herein described.

3. A flexibly-suspended tank connected by a metallic pipe to a fixed car-stove, the discharging end of said pipe being free to move within the stove-coupling, substantially as herein described, and for the purpose stated,

In testimony whereof we affix our signatures in presence of two witnesses.

HERMAN LEVOY.
FRANK DAGWELL.
